INVENTOR

BY Victor J. Evans

ATTORNEY

UNITED STATES PATENT OFFICE.

JOHN TOTH, OF JOLIET, ILLINOIS.

SHIELD.

Application filed December 1, 1926. Serial No. 151,991.

- My present invention has reference to a protective shield for soldiers' use and my primary object is the provision of a shield for this purpose which can be readily arranged and effectively supported on the person of the user and which will not interfere with the free movement of the wearer, permitting him to kneel, lie down or charge with alacrity.
10. A further object is the provision of a shield that comprises two members which are centrally hinged together and which have their outer corners concaved so that the shield when arranged on the wearer will not interfere with his free arm movement, the said shield being provided with straps arranged whereby the device may be quickly arranged upon the wearer and effectively supported, the said device also including means for setting up the shield to provide a member which is V-shaped in plan and for supporting the shield on the ground surface, the shield being centrally provided with a substantially key-hole opening that permits of the passage of the barrel of a firearm therethrough and likewise allows the soldier, when in kneeling or in lying position, to observe conditions in front of the shield.
20. A still further object is the provision of a shield for this purpose whose edges are beveled to serve as deflectors for bullets contacting therewith, the outer face of the shield being composed of layers of tightly compressed material so that the shock of bullets or like missiles contacting therewith will be absorbed and not inflict injury to the wearer of the shield.
25. A further object is the provision of a shield comprising two hingedly connected members of light but tough material of a strength to effectively withstand and prevent the penetration of bullets fired thereagainst and which may be set up on the ground, worn on the front of a soldier in a charge or on the back of a soldier in a retreat.
- To the attainment of the foregoing and other objects which will present themselves as the nature of the invention is better understood, the improvement also resides in certain other novel features of construction, combination and operative association of parts, a satisfactory embodiment of which is disclosed by the accompanying drawings.

In the drawings:

Figure 1 is a front elevation of a shield in accordance with this invention.

Figure 2 is a rear elevation thereof.

Figure 3 is a top plan view thereof.

Figure 4 is a rear elevation but showing the shield in a position to be carried by the user.

Figure 5 is an enlarged detail sectional view approximately on the line 5—5 of Figure 1.

As disclosed by the drawings, the shield comprises two substantially rectangular members 1—1. These members have their upper outer corners concaved inwardly, as at 2. The confronting ends of the members 1—1 are formed with spaced knuckles 3 designed for engagement and for the reception of suitable pintles whereby the members 1—1 are hingedly associated.

The shield has its edges, including its concaved portions 2, and its upper ends beveled, as at 4, and the central knuckle 3 is formed with a key-hole opening 5.

The shield is light and of water-proof material. Each of the members 1 preferably includes plates of steel, indicated by the numeral 6. The outer face of this plate has a facing of thin tough paper 7 which is compressed thereagainst. The steel plate on the inner face of the shield has compressed thereagainst and effectively secured thereto a facing of flax 7', and the outer surface of the flax facing 7' is covered by tough paper 8. A suitable coating of rough material is given the paper facing 8. The outer steel plate has compressed thereagainst a surface 10 of flax, the flax in turn being provided with a facing of old cotton batten 11, and the cotton in turn has a facing 12 of tough paper. The paper is treated with a water proof substance and the laminated elements comprising the members 1 are riveted together along the edges and ends thereof.

Fixed to the diagonally opposite corners of the members 1, on the inner faces thereof are the ends of straps 13, and fixed to the diagonally opposite corners of the said members 1 there are short straps 14 carrying buckles which engage with the straps 13. In this manner it will be seen that the members comprising the shield may be sustained angularly with respect to each other and easily and quickly arranged on the person

of the user. In a like manner the shield may be easily detached and arranged on the back of the user in cases of retreat.

On the inner face of the shield and adjacent to the top and bottom of the respective members 1 there are swingably secured rods 15 which have hooked ends to be engaged in eyes 16 on the said inner faces of the members 1. When the shield is to be carried 10 these rods are received in the said eyes, but the said rods may be arranged in other eyes 17 disposed on the inner faces of the members 1, adjacent to their hinged connection, and the rods are so arranged when the shield 15 is in use. The lower rod 15 may have its hooked end embedded in the ground when the shield is detached from the wearer and arranged on the ground. In this instance, the soldier can observe conditions through 20 the sight opening 5. This opening 5 also permits of the reception of the barrel of a firearm therethrough and not only supports the barrel but permits of the soldier obtaining accurate aim.

25 By constructing a shield as above described any concussion which would usually result from bullets contacting the shield will be absorbed by the elements constituting the outer faces thereof. The shield may be conveniently carried by the straps 13 when not

in use and may, as stated, be easily positioned on or removed from the wearer.

The simplicity of the construction and the advantages thereof will be readily apparent to those skilled in the art to which such invention relates, when the foregoing description has been carefully read in connection with the accompanying drawings.

Having described the invention, I claim:—

40 A shield for the purpose set forth, comprising two substantially rectangular members having their confronting edges provided with interengaging knuckles and pivots received in the knuckles, the central 45 knuckle having a key opening therethrough and the outer corners of the members being concaved, said members having beveled edges and each of said members comprising 50 steel plates having laminated compressed facings thereon, which latter are treated to render the same water proof, adjustable straps on the inner faces and extending from the diagonal corners of the respective members, rods having hooked ends hingedly secured on the inner face of each member and eyes on the said members for the reception of said hooks.

55 In testimony whereof I affix my signature.
JOHN TOTH.
